PILE WIRE LOOM AND METHOD OF
WEAVINGWalter A. Rice, Yonkers, and Frank G. Shinn,
Bronxville, N. Y.

Application April 1, 1933, Serial No. 663,964

37 Claims. (Cl. 139—37)

Our invention relates to certain new and useful pile fabric looms, in which we weave pile fabric having knotted tufts.

The principal purpose of our invention is to form knotted tufts around the warp and preferably also the weft threads of a fabric from a continuously supply of yarn, cutting the tufts or not as desired.

A further purpose is to use continuous tuft yarns in a pile wire loom to form knots having an eye and a loop each, about the warp threads alone or about warp and weft threads in a fabric as desired.

A further purpose is to effect the crossing of warp threads in a pile wire loom by a manipulating device for shifting continuous tuft yarn.

A further purpose is concurrently to divert the warp threads laterally in a pile wire loom to cross them, and to manipulate the tuft yarn in the loom so as to knot it about the crossed warp threads, or the warp and weft threads as preferred, preferably performing the crossing of the warp threads and manipulation of the tuft yarn by needles through whose eyes the tuft yarn passes.

A further purpose is to manipulate continuous pile yarn in a loom by a vertically and laterally movable needle.

A further purpose is to interject warp thread pair crossing mechanism and tuft yarn diverting mechanism within a pile wire loom so as to form tuft yarn knots in the place of the tuft yarn loops at present woven into fabrics by the pile wire looms.

A further purpose is to control the positions of tuft yarns in a pile wire loom by needles having eyes for the tuft yarns and having elongated openings below the eyes for passage and partial control of stiffer warp threads, preferably tapering the elongated openings.

A further purpose is to closely guide the warp threads in a pile wire loom as by fixed reeds and laterally fixed uniformly spaced heddle eyes.

A further purpose is to take up slack in a continuous tuft yarn.

A further purpose is to laterally divert warp threads in a pile wire loom at points back of the lay reed dents, causing crossings to be effected in front of the lay reed dents and to manipulate continuous tuft yarns, one for each pair, from a point back of the lay reed dents so as to form the eyes and loops of knots in front of the lay reed dents either about the warp threads alone or about the warp threads and one or more weft threads, forming tuft yarn loops about pile wires, which

loops form the boundaries of and are parts of adjoining knots, and ultimately cutting the tuft yarn loops by movement of the pile wires or not cutting the loops as desired.

A further purpose is to pass the tuft yarns of a pile wire loom through needles by which they are subsequently controlled, and to manipulate the individual tuft yarns by the needles both laterally and vertically to pass the pile yarn around the crossing point of crossed warp threads longitudinally of the loom, as a preliminary to forming knots, using pile wires as adjuncts to hold the loop portions of the knots between succeeding operations.

A further purpose is to weave patterned knotted rugs, carpets or other knotted pile fabrics from a continuous yarn supply or source on which yarn supply or source the pattern appears in an elongated form but when woven produces a predetermined design or pattern in the fabric.

A further purpose is to use a positive lifting and lowering pile yarn carrier to form a shed for a pile wire, said yarn carrier also being used to cross warp threads during the weaving of the knotted pile fabric.

A further purpose is to make the same loom available by a proper change of cams to form various types of knotted tufts.

A further advantage is that our construction can be attached to the present ordinary types of pile wire looms, including, for example, the commonly known tapestry loom, without the expense of rebuilding the entire loom but creating a wholly new loom in its capability of performing functions and weaving fabrics for which such looms were never previously suited.

A further advantage resides in the fact that when our construction has been added to the ordinary type of loom as herein described, either the ordinary tapestry carpet fabrics, for example, or knotted fabrics, can be woven on the loom, by merely disconnecting engaging parts when it is desired to weave the ordinary tapestry carpet or rug.

Another feature is that the knotted fabrics can be woven on the improved loom at approximately the same rate of production, as is possible on the ordinary type of pile wire loom.

Further purposes will appear in the specification and in the appended claims.

Our invention relates not only to the methods or processes involved but to mechanism by which these methods or processes may be carried out.

To these and other ends, the invention con-

sists of certain parts and combinations of parts, all of which will be hereinafter described.

A practical embodiment of one type of mechanism among the various types by which the invention may be practiced is represented in the accompanying drawings forming a part of this specification, in which, similar characters of reference indicate like parts in all views.

Figure 1 is a front elevation of the loom selected for our illustration.

Figure 2 is a left side elevation of the structure seen in Figure 1.

Figure 3 is a fragmentary enlarged right side elevation of the structure of Figure 1, showing more especially the driving mechanism.

Figure 4 is a fragmentary top plan view, taken from the position of line 4-4 of Figure 3, illustrating the pile wire mechanism.

Figure 5 is a fragmentary sectional side elevation taken on line 5-5 of Figure 1, showing more especially the driving mechanism for the lay, shuttle and pile wire conveyer arm.

Figure 5a is a fragmentary section corresponding to part of Figure 5 but showing a modification of the tuft yarn guide.

Figure 5b is a fragmentary perspective view showing warp thread and tuft yarn relations in Figure 5.

Figure 6 is a fragmentary sectional side elevation, taken on line 6-6 of Figure 1, illustrating the heddle cam driving mechanism and a partial view of the fabric beam driving mechanism.

Figure 6a is a fragmentary perspective showing a tuft yarn guide seen in Figure 6.

Figure 7 is an enlarged front elevation of a heddle, showing one preferred method of equal spacing of heddle wires.

Figure 8 is a sectional elevation, taken on line 8-8 of Figure 2, illustrating the needle cross bar mechanism.

Figure 9 is a fragmentary sectional top plan view taken on line 9-9 of Figure 2, illustrating the needle cross-bar mechanism and heddle arrangement.

Figure 10 is a fragmentary right side elevation, illustrating the needle cross-bar-operating cams.

Figure 10a is a section taken upon line 10a-10a in Figure 10.

Figure 11 is an enlarged front elevation of the needle carrier frame, needle carrier and needle cross-bar.

Figure 12 is an enlarged fragmentary section of the needle carrier and guide bar, taken on line 12-12 of Figure 11.

Figure 13 is an enlarged fragmentary section of the needle carrier frame, taken on line 13-13 of Figure 11, showing the needle cross-bar and guideways.

Figure 14 is a fragmentary sectional left side elevation, taken on line 14-14 of Figure 8, illustrating the cam operating mechanism for the up and down motion of the needle carrier frame.

Figure 15 is the same as Figure 14, except that the needle carrier frame operating cam for weaving the true Sehna knot illustrated in Figures 33, 34, and 35, is shown in place of the one shown in Figure 14.

Figure 16 is a fragmentary sectional left side elevation, illustrating the front heddle operating cam, taken on line 16-16 of Figure 8.

Figure 17 is a fragmentary sectional left side elevation, illustrating the rear heddle operating cam, taken on line 17-17 of Figure 8.

Figure 18 is an enlarged fragmentary sectional side elevation of the needle and chain warp heddle arrangement, taken on line 18-18 of Figure 9, illustrating the fabric formation of the improved knotted tuft fabric as illustrated in Figure 30.

Figure 19 is an enlarged sectional side elevation of the needle and chain warp heddle arrangement, illustrating the first step from the position of the parts in Figure 18 in the formation of the knotted tuft fabric as shown in Figure 30.

Figures 20, 21, 22, 23, 24, and 25 are also enlarged sectional side elevations, illustrating the successive steps required for the forming of the knotted tuft fabric shown in Figure 30.

Figures 18a, 19a, 20a, 21a, 22a, 23a, 24a and 25a are top plan schematic views intended to illustrate the positions of a pair of chain warp threads, a stuffer warp thread, a pile yarn thread and weft threads corresponding to the positions of the parts in Figures 18, 19, 20, 21, 22, 23, 24, and 25, respectively, to show the successive steps required for forming the knotted tufts.

Figures 18b, 19b, 20b, 21b, 22b, 23b, 24b, and 25b are fragmentary enlarged view of parts of Figures 18, 19, 20, 21, 22, 23, 24, and 25, respectively.

Figure 26 is an enlarged sectional side elevation of the needle and chain warp heddle arrangement illustrating the first step in the formation of the knotted tuft fabric shown in Figure 33.

Figures 27, 28, and 29, are enlarged sectional side elevations, illustrating the successive steps required for the formation of the knotted tuft fabric illustrated in Figure 33.

Figures 26a, 27a, 28a, and 29a are top plan schematic views intended to illustrate the positions of a pair of chain warp threads, a strand of pile yarn thread and weft threads corresponding to the positions of the parts in Figures 26, 27, 28, and 29, respectively, to show the successive steps required for forming the knotted tufts of Figure 33 and corresponding to the arrangement illustrated in Figure 26.

Figures 26b, 27b, 28b, and 29b are fragmentary enlarged views of parts of Figures 26, 27, 28, and 29 respectively.

Figure 30 is an enlarged, distorted plan view of the face of one fabric, illustrating the pile yarn and the knotted tuft ends, both before and after pile wires have been withdrawn which have cut the knotted tuft loops and with all the threads shown as though loosely woven.

Figure 31 is a sectional elevation of the fabric illustrated in Figure 30, also shown as though loosely woven.

Figure 32 is a sectional elevation, taken from the position of line 32-32 of Figure 30, illustrating the formation of the completed knotted tuft, both before and after being cut, also shown as though loosely woven.

Figure 33 is a modification of an enlarged distorted plan view of the face of a knotted fabric, commonly known as the Sehna knot, illustrating the pile yarn and the knotted tuft ends, both before and after pile wires have been withdrawn which have cut the knotted tuft loops and is similar to that illustrated in Figure 30, except that chain warp threads only appear, all of the threads shown as though loosely woven.

Figure 34 is a sectional elevation of the fabric illustrated in Figure 33, also shown as though loosely woven.

Figure 34a is a cross section of a modification, similar to Figure 34.

Figure 35 is a sectional elevation, taken from the position of line 35-35 of Figure 33, illustrating the formation of completed knotted tufts, both before and after being cut, also shown as though loosely woven.

Our invention is suitable for manufacture as a new loom unit and is in fact a new loom, but 10 inasmuch as it uses features present in other looms we have found that new construction as a unit is not necessary but that the expense and delay of new loom manufacture can be avoided and the invention can be practiced in existing 15 pile wire looms with comparatively little change in the existing looms.

Among the pile wire looms we have selected for the illustration a loom of the tapestry type, notwithstanding that other pile wire looms can be 20 used, for the reason merely that the tapestry loom lends itself more readily to illustration of the invention than do other looms.

The preferred loom selected is mounted on a main frame 51, on the rear of which are mounted 25 in bearings the stuffer warp beam 52 and the chain warp beam 53. On the uprights is mounted the pile yarn beam 54.

Our invention is suitable for use for fabric with or without stuffer warp threads and the 30 method and mechanism for weaving our knots are identical whether or not the stuffer warp threads be included. Since this is true, we have preferred to illustrate the stuffer warp thread form first, with the understanding that where 35 the additional stiffening and strengthening of the stuffer warp threads are not desired, these stuffer warp threads will merely be omitted without other change.

Assuming that stuffer warp threads are 40 intended to be used, the unwinding of the stuffer warp threads from their beam is controlled by let-off mechanism common to pile wire looms, and therefore not shown in detail, which acts upon the stuffer warp beam shaft 56.

45 As the stuffer warp threads 72 are unwound, they are engaged by a tension device 57 which need not be further described because it is of quite usual form. The threads next pass through lease rods 58, which also are of usual 50 form, and are loosely attached to a tension device rod 59, extending from it forwardly under the guide bar 60, through the open extension portions 62a and 63a between the wires of the heddles 62 and 63 and preferably through a special separating reed 64 and through an elongated tapered slot 82 in pile yarn needle 66, which latter are believed to be new. The stuffer warp threads 55 then pass through the lay dents 67 of lay 68 to the fell 69.

60 The chain warp threads 70 and 71 unwind from the chain warp beam 53. The unwinding of the chain warp threads 70 and 71 is controlled through the beam shaft 71 by means of let-off mechanism common to pile wire looms 65 and therefore not shown in detail.

The chain warp threads 70 and 71 are provided with a tensioning device 78 of a usual form, for which reason further description is not deemed necessary.

70 After leaving the tensioning device 78, the chain warp threads extend forwardly under the guide bar 60 through the heddle wire eyes 62b and 63b and through the special separating reed 64, between pile yarn needles 66, and through 75 the lay dents 67 of the lay 68 to the fell 69.

The unwinding of the pile yarn threads 73 from the pile yarn beam 54 is controlled through the beam shaft 54a by a friction brake 54b of a usual kind employed in pile wire looms and for this reason is not described in further detail.

The continuous pile yarn 73 is then passed through a tensioning device 83 pivoted at 83a and whose pressure is applied by a weight 84 adjustable along the length of an arm 90. The tension device is pivoted in brackets 91 and 100 comprises a bell crank lever whose lower end 92 carries a tension bar 93 to take up any slack in the pile yarn 73 as the latter is drawn from the pile yarn beam 54.

From the tension bar the pile or tuft yarn 15 next passes about a roller 94 which is also supported by brackets 91, and around a locating bar 95 which is capable of adjustment but which, when adjusted, is fixed.

The pile yarn 73 passes through the open extension portions 62a and 63a of the heddles 62 and 63, through the separating reed 64 and then through the eyes 81 of needles 66. These needles are capable of movement and are moved not only horizontally, in a lateral direction, but upwardly 25 and downwardly (preferably vertically). These motions are intermittent during the formation of the knots 88 and 89, as will hereafter more fully be described. The yarn next passes between the lay dents 67 of the lay 68 to the fell 69. 30

For a complete cycle of operation as illustrated two upward and downward reciprocations of the needles take place, one upward movement of the needles being through crossed warp threads and the other through parallel warp threads. Because of the alternation of the sheds the same warp thread is always up when the needle is moved upwardly between the crossed warp threads. The tension in this raised warp thread is increased by lifting it so that in its raised position it has sufficient tension to protect against undue divergence of the warp thread by the pull of the tuft yarn.

The upper warp thread adjacent to the eye of its heddle can, therefore, safely be subjected to 45 the pull of the tuft yarn and can be used as a guide for the tuft yarn. This is seen in Figure 5.

The construction of Figure 5 with the tuft yarn guided by the upper warp thread just below the heddle eye while quite satisfactory could be substituted by a fixed tension bar at some appropriate place. Such a fixed tension bar is shown at 126a in Figure 5a where the tension bar is supported upon an extension 126b of a bracket 126.

The two forms of tension guide for the continuous tuft yarn shown in Figures 5 and 5a are intended to be alternative.

When the lay 68 is back in its rearward position as indicated in Figure 5, the weft threads 75 and 76 are inserted. In the illustration this weft insertion is by means of a shuttle which may be of any usual or preferred kind and hence is not shown in elaborate detail. We recognize that any mechanism may be used which will insert the weft threads and that the use of a shuttle is 65 not essential.

The woven fabric 87 passes over the breastplate 96 and then around the spiked roll 97, whose shaft 98 is supported in bearings in the main frame 51.

The several mechanisms of the loom are actuated in the proper sequence from a crankshaft 99, (Figure 3), extending transversely of the loom and journaled in suitable bearings in the main frame 51. The crankshaft is operated in the 75

usual manner by a manually controlled clutch mechanism, including a cone clutch pulley 100, connected by a belt with other machinery. The direction of rotation is indicated by the arrow.

5 The clutch mechanism includes a usual friction cone clutch, mounted to slide on and turn with pulley shaft sleeve 101, (Figure 8).

The pulley shaft sleeve 101 revolves on a stationary shaft 102, (Figure 8), secured at one end 10 in the main frame 51 and at the other end in the pulley bracket 103, (Figure 3). The sleeve is secured to a pinion 104, (Figure 8), in mesh with a gear 99a secured on the crankshaft 99.

The clutch member 105 (Figure 3), is shifted 15 by a lever 106 fulcrumed on the pulley bracket 103 and connected by a link 107 with an arm 108. The latter is secured on a rocker-shaft 109 which extends longitudinally of the loom and is journaled in the main frame 51.

20 The forward end of the rocker-shaft 109 carries a hand lever 110 under the control of the weaver. This lever extends in a notched guideway 111, (Figures 1 and 3), on the main frame 51.

The clutch is also provided with a friction 25 brake which operates simultaneously with the clutch to stop the rotary motion of the pulley shaft from coasting after the friction clutch members 100 and 105 are disengaged.

When the hand lever 110 is shifted, the oscillation 30 of the rocker shaft 109 swings an arm 112 which is connected by link 113 with bell crank lever 114. Lever 114 operates brake band 115, stopping or starting the loom.

A spring 116 is provided for holding the clutch 35 in a non-acting or disengaged position.

The rotary motion of the crank-shaft 99, (Figure 8), is transmitted to a cam-shaft 117, extending transversely of the loom and supported in bearings on the main frame 51. For the above 40 purpose the crank-shaft 99 is provided at one end with a pinion 118 secured to the crank-shaft 99, and in mesh with a gear 119 fastened upon the cam-shaft 117, so that when the crank-shaft 99 is rotated, a continuous but slower rotary motion 45 is given to the cam-shaft 117. In the illustration this speed has been taken as half the speed of the crank-shaft.

The other end of the crank-shaft 99, (Figures 8 and 10), is provided with a pinion 120 secured 50 to the crank-shaft 99, so that when the crank-shaft 99 is rotated a continuous but slower rotary motion is given to the cam-shaft 117, mounted to rotate freely on the cam-shaft 117. In the illustration this speed has been assumed to be one-fifth 55 of the speed of the crank-shaft.

It will therefore be apparent that the gear ratios of the pinion 118 secured to the crank-shaft 99 and the gear 119 secured to the cam-shaft 117 on the right side of the loom, differ from the ratios 60 of the pinion 120 secured on crank-shaft 99 and the gear 122 secured to the cam sleeve 121 on the left side of the loom, (see Figure 8).

Therefore the picker cams 124 and 125 (Figures 5 and 6) make two revolutions for every one revolution of the cam sleeve 121, (Figures 8, 10, and 10a), carrying the cams for actuating the various devices in the proper sequence, as hereinafter more fully described.

The heddles 62 and 63 are mounted to slide up 70 and down (Figures 8 and 9) in suitable guideways formed on the brackets 126 and 127 attached to and forming a part of the main frame 51. The upper ends of the heddles 62 and 63 are hung on links 128 and 129 (Figures 5, 8, 16, and 17) connected to levers 130 and 131 secured

to transversely mounted rocker-shafts 132 and 133.

The shafts carry levers 134, 134a which are connected through links 135, 135a with levers 136 and 137 (Figures 16 and 17). These latter levers 5 are pivoted on the bracket 138 of the main frame 51 and carry at intermediate points along their lengths rollers 139 and 140. These rollers engage cam grooves in the cams 141 and 142 which are mounted upon the cam sleeve 121. The cam 10 sleeve rotates freely on the cam shaft 117 and is driven by pinion 120 through the gear 122.

When the loom is in operation the crank-shaft 99 is rotated, carrying the pinion 120 in mesh with the gear 122 secured to the cam sleeve 121. 15 This rotates the cams 141 and 142 in the direction shown by the arrow, and the cams 141 and 142 impart an intermittent up and down motion to the links 135 and 135a.

Each of the cams operates to intermittently 20 lift and subsequently lower its own heddle and each of them lifts its heddle while the other heddle is being lowered and lowers its own heddle while the other heddle is being raised.

The links 135 and 135a actuate the heddles 25 through levers 134 and 134a connected by the rocker shafts 132 and 133 with levers 130 and 131, which in turn operate the heddles by links 128 and 129.

The heddle wires 62c and 63c, (Figures 7, 8, 30 and 9), are secured to the heddle frames 62 and 63. It is important that they be equally spaced, thereby maintaining the chain warp threads 70 and 71 in proper alignment for the pile yarn needles 66 as herein more fully described. This 35 novel construction allows free and unobstructed passage between the heddle wires in the open extension portions 62a and 63a for the stuffer warp threads 72 and the pile yarn 73, so that the up and down intermittent motion of the heddles 62 and 63 does not affect the relative positioning of the stuffer warp threads 72 and the pile yarn threads 73 in the shed.

The heddle wire eyes 62b and 63b are of a usual type, and when the heddles rise and fall, 45 carry the chain warp threads 70 and 71 with them, as will presently be described.

The separating reed 64 is secured to brackets 126 and 127 of the main frame 51, (Figures 8 and 9). Its dents 145 are also equally spaced and 50 serve also as separators for the several threads, namely a pair of chain warp threads 70 and 71, a stuffer warp thread 72 and a pile yarn thread 73, all included between each two adjoining dents and all held in proper alignment for the corresponding pile yarn needle 66.

The needle carrier frame 150 is mounted to slide up and down in suitable guideways formed on brackets 126 and 127 on the main frame 51, (Figures 8 and 9) and is guided at the lower end 60 by depending guide bars 147 and 148. The guide bars are secured to the needle carrier frame 150 in suitable ways formed in the lower cross beam 149, of the main frame 51 (Figures 5, 6, and 8).

The upper end of the needle carrier frame 150 65 is hung on links 153 connected to levers 154. The levers are secured to a transversely mounted rocker-shaft 155 pivoted on the top cross-beam 152, of the main frame 51.

The outer end of the rocker-shaft 155 (Figures 8 and 14) has secured to it a lever 156 connected by a link 157 with a lever 158 fulcrumed on a bracket 138 on the main frame 51. The lever 158 carries a friction roller 159 engaging cam 75

grooves in the cam 160 secured to the cam-sleeve 121.

The needles 66 are mounted in a needle carrier 162, (Figures 8, 11, 12, and 13), to slide horizontally in guideways 163, formed on the lower rail 164 of the needle carrier frame 150.

The needle cross (shifting) bar 165 is mounted to slide horizontally, in suitable guides 161 and 161a projecting from the lower sides of brackets 126 and 127 (Figure 8) of the main frame 51, and is connected by a link 166 to one arm of a bell crank 167 pivoted in a bracket 168. The other arm of the bell crank is connected through a link 169 with a lever 170 pivoted at its opposite end in a bracket 138, (Figure 10). The lever 170 carries a friction roller 171 at an intermediate point in the length of the lever and this roller is held in engagement with the peripheral cam surface of the cam 172 by a spring 173, (Figure 8). The cam 172 is mounted upon the cam sleeve 121, and its peripheral surface is provided with cam depression 172a and a cam projection 172b.

When the loom is in operation and the cam-sleeve 121 is rotated in the direction shown by the arrow, (see Figure 10), the cam 160 imparts an intermittent up and down motion to the link 157, (Figure 14), connected to the lever 156, secured to the rocker shaft 155, swinging the lever 154, whereby the needle carrier frame 150 is moved intermittently in an up-and-down direction, (Figures 6 and 8).

The cam 172, (Figures 8, 10, and 10a), imparts an intermittent up and down motion to the link 169 through roller 171 upon lever 170. The link 169 is connected to one arm of bell crank lever 167. The other arm of this bell crank lever 167 connects with the needle cross bar 165 by link 166, whereby the needle cross bar 165 is given an intermittent horizontal motion crosswise of the loom, shifting the needle carrier 162 with the needles 66 secured thereon as indicated in Figures 8 and 9. The extent of this shifting movement is slight, carrying each of the needles from a position on the outside of one chain warp thread of its pair to a position on the outside of the other chain warp thread of the same pair and slightly greater than the spacing from the center of one warp thread pair to the center of the next adjoining warp thread pair, as will be hereinafter more fully described.

In order to permit the needles to have up and down movement within the needle cross bar 165 without interfering with the use of this cross bar to determine the lateral positions of the individual needles with great accuracy, this cross or shift bar 165 is slotted for each needle a few thousandths of an inch wider than the thickness of the needle. Needle carrier frame 150 and the needle carrier 162 with its needles 66 can therefore lift and lower the needles coincidently with or separately from the lateral movement of the cross or shift bar 165 and of the needles shifted by it.

In order to provide for differences in thickness of chain warp threads, desirable for different weaves, the extent of lateral shifting movement of the needles is made adjustable by variation in the position of a stop 143 held in adjusted position within the frame by a lock nut 144. It fits within a bracket 161a and the head is engaged by a projection 165a from the needle cross bar 165.

To make the adjustable stop 143 effective, the depressions 172a and 172b are deeper than would be required to shift the needle cross bar 165 the

proper distance. Consequently the friction roller 171 is prevented from riding in the bottom of the depressions in the cam 172 by the adjustable stop 143.

The lay 68 (Figures 5 and 6) is of any usual construction, having lay dents 67 and a shuttle raceway 177 supported on a rail 176 between layswords 178. The layswords are secured to a rocker-shaft 179 pivoted in the main frame 51. The backward and forward movement of the lay 10 is actuated by the crank-shaft 99, having eccentric crankpins 180 and links 181 pivoted in the laysword arms 182, (Figures 5, 6, and 8).

The shuttle mechanism illustrated is also of a usual construction common to this type of loom. The shuttle boxes 183 and 184 and the shuttle raceway 177 are supported on the rail 176 between the layswords 178, (Figures 1, 5, and 6).

The picker sticks 185 and 186 are pivoted in a bracket 187 (Figures 1 and 3) secured to the rocker-shaft 179 and are held in a position at rest, as shown in Figure 1, by springs 188 connected to the main frame 51.

The picker sticks 185 and 186 are oscillated 25 backwards and forwards intermittently, and are timed in such a way that they alternate in throwing the picker blocks 189 toward the center of the loom when the lay 68 is in a rearmost position, as shown in Figures 5 and 6.

The picker blocks 189 are provided with slots for the engagement of the picker sticks 185 and 186 and are arranged to slide lengthwise in the shuttle raceway 177.

It will therefore be understood that the alternating oscillating motions of the picker sticks 185 and 186 will throw the shuttle 190 within the guiding shuttle raceway 177 from one side to the other, as will be herein more fully described.

The picker sticks are actuated by straps 191, 40 one for each side, secured to levers 192 pivoted in brackets 193 on the main frame 51, and are connected by other straps 194 to rocker-levers 195 and 195a, fulcrumed in brackets 196 on the lower cross beam 149. Levers 195 and 195a are 45 actuated by picker cams 124 and 125 secured to the camshaft 117 and are diametrically opposite, thereby alternating the oscillations of the picker sticks 185 and 186 and intermittently throwing the shuttle 190 from one side to the other. 50

The shuttle 190 is of the usual form employed in this type of loom and detailed description is therefore deemed unnecessary.

The pile wire mechanism is also of a usual construction common in pile wire looms. 55

The pile wire carriage 225 (Figures 3 and 4) is slidably mounted on a rail 226 supported on a bracket 222 on the main frame 51. Mounted on the pile wire carriage 225 is a bayonet arm 227, that engages a slot 228 in the rear end of 60 any pile wire 85.

The pile wire carriage 225 is given a transverse intermittent motion along the rail 226 by a bell-crank lever 230 (Figure 1) fulcrumed in a bracket 223, on the main frame 51 and connected by a link 231, with a lever 232 pivoted in a bracket 224, on the main frame 51 (Figure 3).

On the lever 232 is journaled a friction roller 233 which travels on the peripheral face of a cam 234, secured on the cam shaft 117. The 70 inner face of the rim of the cam 234 is engaged by a friction roller 235, journaled on a spring pressed lever 236 fulcrumed on a bracket 237 of the lever 232. Lever 236 with friction roller 235 and friction roller 233 are held in engagement with 75

the inner and outer faces of the rim of the cam 234, so that when the cam-shaft 117 is rotated, the lever 232 is given positive up and down motions.

Secured to the rail 226 is a vertically inclined track 238, (Figure 4), on which is slidably mounted a pile wire carrier 239, connected by a link 240 with an arm 241 having a hopper 242 that engages the outside rear end of the pile wire 85. The hopper is frictionally held in engagement 10 with the pile wire by a spring 243.

The pile wire carries a knife 244 at its front end if the tufts are to be cut, but is without a knife if the tufts are not to be cut.

When the pile wire carriage 225 is moved backward and forward by the rotary motion of the cam 234, it carries with it the pile wire carrier 239, (Figure 4).

When the loom is in operation, the bayonet arm 227 engages the slot 228 in the first pile 20 wire 85, of those in the fabric as shown in dotted lines in Figure 4. The pile wire with its knife 244 (if the pile loops are to be cut, otherwise without a knife) is withdrawn from the pile yarn loops 73a, cutting the loops or not cutting them 25 in the operation.

The front pile wire 85 is then brought by the bayonet arm to the position shown, in Figures 4 and 5, and its slotted rear end is pressed into the hopper 242. Meanwhile the other end of the 30 pile wire is picked up by the conveyor lever 245 carrying a friction roller 246 in guideways 247, formed on a bracket 248, on the main frame 51.

The conveyer lever 245 is pivoted on a link 249, (Figure 5), pivoted in a bracket 250 on the main 35 frame 51, and actuated by a link 251 connected to a lever 252 fulcrumed in the main frame 51 and carrying at an intermediate point in its length a friction roller 253 traveling on the peripheral face of the cam 254, secured to the cam-shaft 117.

40 On the return motion of the pile wire carrier 239, the pile wire 85 is inserted in the shed 86, in position to take its place at the rear of the pile wires already placed and is beaten up by the lay 68. The pile wire is then released from the 45 hopper 242, as will be hereinafter more fully described.

The spiked roll 97 common to this type of loom, has its shaft 98 journaled in suitable bearings on the front end of the main frame 51, (Figures 1, 50 2, 3, 5, 6, and 9). On the left end of said shaft 98 is secured a gear 255, (Figure 2), in mesh with a pinion 256 secured on a stud 257, in the main frame 51. On the stud 257 is secured a ratchet wheel 258 engaged by an advancing pawl 259 pivoted on an arm 260 which in turn is pivoted on the stud 257.

60 A locking pawl 261 (Figure 2), pivoted on the main frame 51, is provided for holding the ratchet wheel 258 as it is advanced by the advancing pawl 259. The latter is given a swinging motion by a thrust rod 262, guided in a bracket 263 on the main frame 51.

A shaft 179 carries a bracket 187 which operates with the shaft and upon which is mounted 65 an arm 264 by which the lower end of thrust rod 262 is moved in an arc generally up and down about the center of the shaft 179. This causes the thrust rod to move in a general longitudinal direction at the same time that it swings slightly 70 through the guide 263. The amount of movement is small. The construction is one common in this art so that further detailed description is not necessary. It is to be understood, however, that as the gear 255 is revolved by the mechanism described above, the spike roll 97 takes up 75

the fabric woven in proportion to the amount woven.

It will be evident that the mechanism described forms a complete pile wire loom capable with proper timing of the parts and without any other 5 use of the needles than for such vertical shifting as was previously performed by a heddle, of weaving pile fabric cut or uncut according to the character of the wires used. It does not, of course, form a knotted tuft fabric and places the 10 tufts about the weft threads.

It is true that heddles will have to be used to lift and lower the continuous pile yarn if the needles be not used for this purpose.

The loom contains the necessary mechanism 15 for supporting and vertically shifting the warp threads, including stuffer warp threads, if desired, means for inserting and withdrawing pile wires, means for placing weft thread and beating it up, tuft yarn supporting mechanism, needles 20 capable of being lifted and lowered in place of the usual heddle, and mechanism to pass the weft under tuft yarns or over them as desired. From this standpoint, the needles and their lifting and lowering mechanisms would correspond with the 25 normal heddle control of the tuft yarn. Into the loom construction, as stated generally in this paragraph, old in the art except for the use of needles instead of heddles to divert the tuft yarn up and down, so as to pass tuft loops about the 30 weft thread, we insert mechanism by which the entire character of the loom is changed in so far as the tuft yarn manipulation is concerned and in so far as we weave knots about warp thread alone or about warp thread and weft thread together, as distinguished from weaving mere loops and these about weft thread.

For our purposes we have further altered the timing and have supplied manipulation by which the tuft yarn may not only be lifted and lowered but shifted laterally and by which the warp threads can be crossed and the tuft yarn can be shifted with respect to the warp threads. We have also changed the method of inserting the 35 stuffer warp threads.

The several mechanisms described above are now in a position of rest, the shuttle 190 being at the left-hand side of the loom, as in Figures 1 and 18. The lay is in its rearmost position and the needle 66 at the extreme left position, a wire 50 85 and a weft 75a just having been placed.

As the operation of the loom proceeds, the combined action of the crank-shaft 99 and the crank pins 180 shown in Figures 5, 6, and 8 actuate the lay 68 to the dotted position and beats 55 up the wire 85 and the weft 75a, shown in Figure 19. As the lay 68 is momentarily held at the fell, end the crank-pins 180 pass over the center, rotation of the cam-sleeve 121 carrying the cam 160 continues.

This cam 160 by the offset 160b, shown in Figure 14, in turn through its connections moves the needle 66, (having an endless pile yarn 73 threaded through its eye 81), to its lowermost position, forming the loop 73a over the wire 85.

Continuing the rotation of the crank-shaft 99, the lay 68 swings back to its rearmost position, shown in full lines in Figure 19.

As the lay 68 is in its rearmost position, as shown in full lines in Fig. 19, and the right hand 70 chain warp thread 70 is held in the upper shed by the heddle 63, a shot of weft thread 16a is inserted by the shuttle 190, through the lower shed, over the pile yarn 73, the left hand chain warp thread 71 and the stuffer warp thread 72, as illus- 75

trated in Figures 19 and 19a. This movement is effected by the action of the cam 125 on the lever 195, shown in Figure 6.

The crank-shaft 99 continuing its rotary motion, actuates the lay 68 and beats up the shot of weft thread 76a that has been inserted in the shed, and a portion of the eye 74a of the knotted tuft is formed, as shown schematically in Figure 20a.

At the same time the needle 66 is shifted to the right of the right-hand chain warp thread 70 and crosses the pile yarn under the right-hand chain warp thread 70. This is illustrated schematically in Figures 20 and 20a. This movement of the needle 66 is caused by the depression 172a in the cam 172, shown in Figure 10.

While the lay 68 is held momentarily at the fell 69, the cam 160, (Figure 14), continues its rotation in the direction of the arrow, and as the dwell 160c on the cam 160 approaches the friction roller 159 secured to the lever 158 which actuates the needle frame 150 carrying the needles 66, the needle 66 starts upward on the right of the right-hand chain warp thread 70, shown in Figure 20.

The sleeve 121 to which is secured the cam 160 also has secured to it the cams 141 and 142 and through their connections, simultaneously with the upward movement of the needle 66, actuate the heddles 62 and 63, (see Figures 16 and 17) and bring them to an approximately center position, as indicated in Figure 20.

At about the time the heddles assume the positions in Figure 20 the friction roller 171 has passed the depression 172a in the cam 172 and through its connection actuates the needle cross-bar 165 in a direction across the loom to the left, shifting the needle carrier 162 in the guideways 163 to the left, as indicated in Figure 21a.

Since the upward movement of the needle 66 is simultaneous with the shifting of the heddles, changing the warp shed, it will be apparent that the chain warp thread 70 drops down as the needle 66 begins to rise. Therefore the chain warp thread 70 being on the left side of the needle 66 is carried to the left of the left hand chain warp thread 71 crossing the warp threads of the pair.

The chain warp threads 70 and 71 are now crossed, with the right-hand chain warp 70 under the left-hand chain warp 71 and the pile yarn 73 also crossed under the left-hand chain warp thread 71, as plainly indicated in schematic Figure 21a.

The lay 68 having beaten in the weft thread 76a as the heddles change, shown in Fig. 20, firmly binds the eye 74a into the fabric.

The rotation of the cams 141 and 142 and their connections have changed the relative positions of the heddles 62 and 63 and of the corresponding chain warp threads.

The rotary motion of the crank-shaft 99 again actuates the lay 68 to swing it back to its rear-most position, as shown in Figure 21, and simultaneously the cam 160 actuating the needle carrier frame 150 comes to the dwell 160c, (see Figure 14). It has raised the needle 66 with the pile yarn 73 threaded through its eye 81, to its upper-most position between the crossed chain warp threads 70 and 71, and completes the loop 74c, as in Figure 21a.

This completes the formation of one knot and corresponds to one-half revolution of the cam-sleeve 121, one complete revolution of the cam-

shaft 111, (causing two picks of the shuttle), and two revolutions of the crank shaft 99. This likewise corresponds to two beats of the lay and is the first half cycle of the loom operation.

Since two knots are formed for each complete cycle of the loom, it will be understood that the formation of the second knot is now about to be described.

The left hand chain warp thread 71 is now in the upper shed and the right hand chain warp 10 thread 70 is in the lower shed.

The tapered slot within the needle permits the stuffer warp thread 72 to maintain its position in the shed when the needle rises, as indicated in Figure 21.

While the crankpins 180 swing over the center, and the lay is thus held in rearmost position, momentarily at rest, the pile wire mechanism is actuated by rotation of cam 234 and a pile wire 85a is inserted in the upper shed under the pile 20 yarn 73. At the same time the cam 124 actuates the lever 192a and a shot of weft thread 75b is inserted by the shuttle 190 through the lower shed. It picks over the right-hand chain warp thread 70 and under the stuffer warp thread 72 25 and the left-hand chain warp thread 71. It will be noted that the loop 73a over the pile wire 85 is formed to the left of the left-hand chain warp thread 71 instead of between the chain warp threads 70 and 71 as in the next cycle, as herein-after described.

After the wire and weft have been inserted, the needle 66 is dropped to its lowermost position, as shown in Figure 22, by the offset 160d on the cam 160 and by its connections, shown in Figure 35 14. This allows the chain warp threads 70 and 71 to uncross and thereby forms the loop 74c, and part of the eye 74d, of the knotted tuft after being carried over the pile wire 85a, as plainly indicated schematically in Figure 22a.

The continued rotation of the crank-shaft 99 again actuates the lay 68 and beats up the pile wire 85a and the weft thread 75b to the fell 69, binding the chain warp threads 70 and 71, and the weft thread 75b firmly and also binding the 45 knot so that it will not loosen.

As the lay 68 is momentarily held up to the fell 69, by the crank-pins 180 as they pass over the center, the pile wire mechanism is actuated and the pile wire carriage 225 with bayonet arm 50 227 engages the slot 228 in the front pile wire 85, (see Figure 4).

As the crank-shaft 99 again continues its rotary motion, the lay 68 swings back towards its rear-most position, as in Figure 23. The pile wire carriage 225 by the action of the cam 234, withdraws the pile wire 85b. If the pile wire carries a knife 244 on one end, the knife cuts the row of tufts 73a looped over said wire and it places 60 the front (knife) end of the pile wire 85b in a position again to be inserted in the shed, as shown in Figure 4, in the proper sequence.

When the lay 68 reaches its rear-most position, as shown in Figure 23, the shuttle 190 is thrown 65 to the right, through the shuttle raceway 177, by the action of the cam 125, and a shot of weft thread 76b is inserted in the lower shed, over the right-hand chain warp thread 70, the pile yarn 73 and the stuffer warp thread 72, and under the left-hand chain warp thread 71, as indicated 70 schematically in Figures 23 and 23a.

The crank-shaft 99 continues its rotary motion, actuates the lay 68, beats up the weft thread 76b, 75

and firmly binds the loop $74c$, and the eye $74d$, into the fabric, as shown in Figs. 24 and 24a.

At the same time the needle is shifted to the right of the right-hand chain warp thread 70 .
5 This is illustrated schematically in Figure 24a. This movement of the needle 66 is caused by the depression $172a$ in the cam 172 .

As the lay 68 is held momentarily up to the fell 69 by the crank-pins 180 as they pass over 10 the center, the cam 160 (see Figure 14) continues its rotation in the direction of the arrow and as the dwell $160a$ on the cam 160 approaches the friction roller 159 secured to the lever 158 which actuates the needle frame 150 carrying 15 the needles 66 , the needle 66 starts upward on the right of the right-hand chain warp thread 70 .

In this second one half cycle it will be noted that the right-hand chain warp thread 70 is shifted from the lower shed to the upper shed. 20 Consequently when the needle 66 rises and shifts to the left, and the chain warp thread 70 being in the upper shed, the needle does not carry the right-hand chain warp thread 70 with it, as in the previous half cycle. Therefore the chain 25 warp threads are not crossed in forming the knot made in the second half cycle of the loom operation.

The cams 141 and 142 through their connections actuate the heddles 62 and 63 and bring 30 them to an approximately center position, as indicated in Figure 24.

The lay 68 is held firmly up against the beaten row of knotted tufts 88 during the change of heddles 62 and 63 , so that the knots 88 will not 35 loosen when the chain warp threads 70 and 71 change their relative positions during the up and down movement given to the chain warp threads 70 and 71 .

Continued rotation of the cams 141 and 142 40 changes the heddles to the position shown in Figure 25, carrying the chain warp threads 70 and 71 with them, that is, the heddle 63 moves into an uppermost position, while the heddle 62 moves into the lower position.

45 The left-hand chain warp thread 71 now being in the lower shed as shown in Figure 25, as the needle 66 shifts back again to the extreme left, the chain warp thread 71 is diverted slightly by the needle 66 , shown in Figure 25a.

50 The cam 160 actuating the needle frame 150 carrying the needles 66 continuing its rotation, raises each needle with the pile yarn 73 threaded through its eye 81 to its uppermost position between the two chain warp threads 70 and 71 .

55 As the lay 68 swings back, and the needle 66 reaches its uppermost position between the two chain warp threads 70 and 71 , as shown in Figures 25 and 25a, and the crank-pins 180 momentarily hold the lay 68 in its rearmost position as 60 they swing around the center, the pile wire mechanism is actuated by the rotation of the cam 234 and inserts a pile wire $85b$ through the upper shed.

It will therefore be apparent that the loop $73a$ 65 over the pile wire $85b$ is formed between the chain warp thread 70 and the chain warp thread 71 , instead of to the left of the left-hand chain warp thread 71 as in the previous cycle.

The pile wire passes under the pile yarn 73 and 70 simultaneously the cam 124 actuates the lever $195a$ and a shot of weft thread $75c$ is inserted by the shuttle 190 , picking over the left-hand chain warp thread 71 and under the right-hand chain warp thread 70 and the stuffer warp thread 72 , 75 as indicated in Figures 25 and 25a.

The above completes the operation of putting in the two rows of knotted tufts 88 over the pile wires $85a$ and $85b$ and is one complete revolution or cycle of the cam-sleeve 121 , two revolutions of the cam-shaft 117 and four revolutions 5 of the crank-shaft 99 .

At this point the various cams and other operating mechanisms assume the positions as illustrated in the accompanying drawings.

When the lay 68 again reaches the fell 69 on 10 the first half cycle (second series of knots) as in Figure 19, and the cam 160 continues its rotation in the direction of the arrow, the cam 160 by the offset $160b$ (see Figure 14) in turn through its connections moves the needle 66 to its lower- 15 most position.

The lay then swings back to its rearmost position, the needle 66 and the chain warp threads 70 and 71 again assuming the positions as indicated in full lines in Figure 19. 20

The right-hand chain warp thread 70 is held in the upper shed and another shot of weft $75c$ (see Figures 30 and 31) is inserted through the lower shed.

The crank-shaft 99 continuing its rotary motion 25 actuates the lay and beats up the shot of weft $75c$, the various parts assuming the positions as in Figure 20.

Simultaneously the needle 66 is shifted again to the right of the right-hand chain warp thread 30 70 and crosses the pile yarn under chain warp thread 71 . This shifting of the needle 66 is caused by the depression $172a$ in the cam 172 .

In this the first half cycle of operation, second series of knots, again it will be seen from Figures 35 20 and 21 that since the upward movement of the needle 66 is simultaneous with the shifting of the heddles changing the warp shed, the chain warp thread 70 drops down as the needle 66 begins to rise. Therefore the chain warp thread 40 70 being on the left side of the needle 66 is carried to the left of the left-hand chain warp thread 71 .

Because of this position of the chain warp threads 70 and 71 they are again crossed in 45 this part of the cycle. When the dwell $160c$ (Figure 14) is reached during operation of cam 160 the needle carrier frame 150 is raised, raising the needle 66 with the pile yarn 73 threaded through its eye 81 to its uppermost position between the crossed chain warp threads 70 and 71 . 50

It will therefore be apparent that the loops $73a$ over the pile wires 85 and $85b$ are formed between the chain warp thread 70 and the chain warp thread 71 instead of to the left of the left hand chain warp thread 71 , as in the second half of 55 the cycle, where it is seen that the loop $74c$ over the pile wire $85a$ is to the left of the left-hand chain warp thread, shown in Figures 22a and 23a.

The cams 141 and 142 continuing their rotation 60 change the relative positions of the heddles 62 and 63 , carrying the corresponding chain warp threads with them. The chain warp threads again assume the positions as illustrated in Figures 21, 21a, and 21b, and the operation is repeated as above throughout the length of the 65 fabric.

It will be noted that the knot woven above conforms to our broad description of the knots woven by us in that it is characterized by an eye and a loop and that the eye and the loop each includes 70 one of the warp threads of the pair of warp threads upon which the knot is formed; but that the knot believed to be broadly new with us, differs from the recognized Persian or Sehna knot in that it binds together not only warp threads 75

but also one or more shots of weft thread passing through the knot. In the illustration the weft thread passes through the eye of the knot and is bound to the warp thread within the same eye and also through the loop of the knot to the adjoining warp thread of the pair.

Our loom is suited not only to forms of this new knot, which we have for convenience called a Sehna type knot, but also to weave the old Persian or Sehna knot; and we believe that it is broadly new to weave a plain Persian or Sehna knot in a pile loom or from continuous pile or tuft yarn. The change of course requires a slight change in the timing of the mechanism, in the present illustration requiring merely a change in one cam by which the needle is manipulated, the cam by which it is raised and lowered.

We will next describe the slight modification of the loom, previously explained, by which the Persian or Sehna knot is placed about the warp threads only without inclusion of weft within the knots.

To weave the plain Persian or Sehna knot, we use a cam 270 (Figure 15) having, as compared with the cam 160, a shorter dwell on the offset portions 270d and 270b, all the other parts of the loom being identically as described above.

The operation of the loom is changed in that the loom now inserts two shots of weft threads in the shed before the needle 66 carrying the pile yarn 73 through its eye 81 drops down to its lowermost position.

The needle is held in the upper position by longer dwells 270a and 270c on the cam 270 and therefore the eyes 74f and 74g of the Sehna knots 89 are formed around under the chain warp thread 70 only, whereas, in the knotted tuft described previously, the eyes 74a and 74d are formed around the chain warp thread 70 and also the weft thread 76a and 76b respectively, as will be noted in the schematic illustrations in Figures 22a to 29a inclusive, and also in Figures 30 to 35, inclusive.

In the operation of this modified form of the loom for making knots about warp threads alone; the crank-shaft 99 and the cams 141, 142 (Figures 16 and 17), actuate the heddles 62 and 63, and cams 270 and 172 (Figures 10, 10a, and 15) operate the needle 66 which carries an endless pile yarn 73 through the eye 81. The needle 66 is moved to its uppermost position by the cam 270. The shed is wide open and the lay 68 is in its rearmost position after having beaten up the pile wire 85a and the weft thread 76b, as shown by the dotted position of the lay 68 in Figure 26. As the lay swings back again to the position shown in full lines in Figure 26, another shot of weft thread 76b is inserted as the needle 66 is held in its uppermost position by the longer dwell 270a on the cam 270. This is desirable but obviously not essential. The number of weft shots is the same as in the Sehna type form but their distribution, as seen above, makes a marked difference in the knot woven.

The crank-shaft 99 continues its rotation and actuates the lay 68 and beats up the weft thread 76b, the lay 68 being held momentarily, up to the fell 69, as the crank-pins 180 swing around the center.

The cams 270 and 172 rotating in the same direction, through their connections drop the needle 66 to its lowermost position, as shown dotted in Figure 27. This is caused by the offset 270b on the cam 270. As the cam 270 continues its rotation the friction roller 159 (secured to the lever 158) travel-

ing in the offset cam groove 270b approaches the dwell 270c. At this point the depression 172a on the cam 172 causes the needle 66 to shift to the right of the right-hand chain warp thread 70, and to cross the pile yarn 73 under the right-hand chain warp 70. This is illustrated schematically in Figures 27 and 27a.

The cam 270, continuing its rotation through its connections, as the friction roller enters the dwell 270c, raises the needle 66 on the right of the right-hand chain warp thread 70.

The sleeve 121, to which is secured the cam 270, also has secured to it the cams 141 and 142 which, through their connections, simultaneously with the upward movement of the needle 66 actuate the heddles 62 and 63 (see Figures 16 and 17) and bring them to an approximately center position, as indicated in Figure 27.

At about the time the heddles assume the positions in Figure 27 the friction roller 171 passes 20 the projection 172b in the cam 172 and, through its connections actuates the needle cross-bar 165 in a direction across the loom to the left, shifting the needle carrier 162 in the guideways 163 also to the left, as indicated in Figure 28. 25

Since the upward movement of the needle 66 is simultaneous with the shifting of the heddles, changing the warp shed, it will be apparent that the chain warp thread 70 drops down as the needle 66 begins to rise. Therefore the chain 30 warp thread 70 being on the left side of the needle 66 is carried to the left of the left-hand chain warp thread 71, crossing the chain warp threads 70 and 71, with the right-hand chain warp thread 70 under the left-hand chain warp 35 thread 71, as indicated in schematic Figures 28a and 28b. This completes the formation of the eye 74g and the loop 74h.

The rotation of the cams 141 and 142, through their connections, has changed the relative positions of the heddles 62 and 63, carrying the corresponding chain warp threads with them. The rotary motion of the crank-shaft 99 again actuates the lay 68 to swing back to its rearmost position, as shown in Figure 28, and simultaneously 40 the cam 270, actuating the needle carrier frame 150, comes to a dwell 270c (Figure 15), and raises the needle 66 with the pile yarn 73 threaded through its eye 81, to its uppermost position between the crossed chain warp threads 70 and 71. 50

The left-hand chain warp thread 71 is now in the upper shed and the right-hand chain warp thread 70 in the lower shed.

At this point the pile-wire mechanism is actuated by the rotation of the cam 234 and as the 55 lay 68 is in a rearmost position at rest, momentarily, while the crank-pins 180 swing over the center, the pile wire 85b is inserted in the upper shed, under the pile yarn 73. At the same time the cam 124 actuates the lever 195 and a shot of 60 weft thread 75c is inserted by the shuttle 190, through the lower shed, picking over the right-hand chain warp thread 70 and under the left-hand chain warp thread 71.

The longer dwell 270c on the cam 270 holds the 65 needle 66 in its uppermost position, shown dotted in Figure 29, and allows the lay 68, actuated by the crank-shaft 99 to beat up the pile wire 85b and the weft thread 75c and swing back to its rearmost position, shown dotted in Figure 29, for 70 another shot of weft thread 76c, before the needle is dropped down to its lowermost position by the offset 270d on the cam 270. This allows the chain warp threads 70 and 71 to uncross, as indicated in schematic Figures 29a and 29b, thus forming the 75

loop 74e around the left-hand chain warp thread 71 and the eye 74f around the right-hand chain warp thread 70.

Continued rotation of the cams 141 and 142 actuates the heddles 62 and 63 and the chain warp threads 70 and 71 again assume the positions as illustrated in Figures 26, 26a and 26b and the operation is repeated as above, throughout the entire length of the fabric.

From the foregoing description, it will be apparent that for every four picks of the shuttle, the cam shaft 117 makes two revolutions, and the cam sleeve 121 makes one revolution, the operation repeating itself every four picks, but the successive rows of knotted tuft ends 88a and 88b, also 89a and 89b, are staggered in their respective positions in the fabric, (that is are reversed to face oppositely) as indicated in Figures 30 and 33. The loop 73a over the pile wire 85b lies on the left of the chain warp thread 70 and the loop 74a over the pile wire 85a lies on the right of the chain warp thread 71.

As the pile wires 85 are withdrawn and the loops 73a are separated by the cutting action of the knife 244 on each pile wire, (cutting being normally contemplated), the tuft ends 89a and 89b in Figure 33, appear on the face of the fabric in a staggered alignment, thus eliminating the tendency for the tufts to appear in successive straight rows as in ordinary fabrics.

It will also be understood that the knotted tufts may be different in color, if a patterned pile yarn is used, to produce a predetermined design in the fabric.

It will be noted that by the arrangement described, the stuffer warp threads 72 pass through the open extended portions 62a and 63a of the heddles 62 and 63, in which movement is facilitated by the uniform and fixed spacing of the 40 heddle wires (Figure 7). They also pass through the separating reed 64 and through the tapered slot 82 in the needle 66 and move up and down in unison with the pile yarn 73. The lost motion due to the length of the tapered slot 82 however, allows the stuffer warp threads 72 to maintain a position in alignment with the chain warp threads in two positions including that of Figure 18, where the needle 66 is in its uppermost position.

The pile yarn 73 is carried to a higher level than the stuffer warp thread 72, thus allowing the pile wire to be inserted above the chain warp 70 and the stuffer warp thread 72, and under the pile yarn 73, and the weft is inserted under the stuffer warp thread 72.

In Figure 19 the stuffer warp thread 72 is shown in the lowermost position and the weft is inserted over the stuffer warp thread 72, the pile yarn 73 and the chain warp thread 71, and under the chain warp thread 70.

The movement of the heddles 62 and 63, is wholly independent of the movement given the needle 66 carrying the stuffer warp thread 72.

By this arrangement, the weft threads 75 and 76 and the chain warps 70 and 71 are interwoven with the stuffer warp threads 72 in the manner described, giving the fabric a stronger and stiffer back.

It will also be understood that the stuffer warp threads 72 can be omitted entirely from the fabric without any other change whatsoever in the construction of the loom, and without in any way changing the structure of the knotted tuft. In order to emphasize this, true of both forms, the 75 stuffer warp threads have been omitted from the

second form illustrated schematically in Figures 26-29, 33-35.

Considering only the diagrammatic Figures 18 to 29 and the knots shown in Figures 30 to 35 and indicating the stuffer warp thread positions for the purpose merely of showing that the lost motion within the slot of the needle allows the stuffer warp thread to be interwoven with the chain warp threads and weft threads to special advantage, the operation is as follows:

It will be understood that the lay is held at the fell after each beating up operation during any shifts that are made in any of the threads, whether it be resheding the chain warp threads by the heddles or altering the position of the tuft 15 yarn or the stuffer warp thread by movement of the needle.

In Figure 18 the chain warp threads are shedded with thread 70, the right hand thread up, and thread 71 down and the needle not only 20 holds a tuft yarn up, giving room for insertion of pile wire 85 between it and the upper chain warp thread, but holds the stuffer warp thread 25 in the upper shed so that the weft thread 75a is introduced below chain warp thread 70 and stuffer warp thread 72. The pile wire 85 and weft thread 75a are then beaten up to the position seen in Figure 19 and the needle, which had been raised between the two uncrossed warp threads 70 and 71, is lowered so that both the 30 stuffer warp thread and the tuft yarn lie in the lower shed.

Lowering the tuft yarn 73 forms the beginning of the eye 74a and prepares for the shifting of the needle to the right of the right chain warp 35 thread 70, thus forming the start of the eye 74a in the crossing of the tuft yarn to the right beneath the chain warp thread 70. This is best seen in Figure 20a.

Because we are now weaving not only a knot 40 having an eye and a loop, each about a chain warp thread, but that particular form of this knot having a weft thread through the eye, the weft thread 76a is inserted at this point over the tuft yarn so that when the weft thread is 45 beaten up the portion of the knot 74a seen in Figure 20a will include not only the chain warp thread 70 but the weft thread 76a.

Because the tuft yarn must be passed up on the right of the chain warp thread 70, which in 50 our discussion above was in the upper position, this chain warp thread is lowered and at the same time chain warp thread 71 is raised, resheding the chain warp threads. While the shedding is taking place, the needle rises slightly to the right of the right-hand chain warp thread 70 until the needle is high enough to carry the right-hand chain warp thread with it when the needle is moved laterally to the left to the position seen in Figure 21a.

During this movement to the left, the chain warp thread 70 passes below the chain warp thread 71 and to the left beyond it, carrying both the tuft yarn and chain warp thread 70 beyond chain warp thread 71. This crosses the chain 65 warp threads, not only at this point but at another point between the needle and the beams. Since we are interested in that crossing only that lies between the needle and the fell, we will consider it alone and disregard the crossing 70 formed between the needle and the beam, which, however, is effective in later straightening out the chain warp threads into parallel alignment.

The needle is next raised from its position of Figure 20 to its uppermost position as seen in 75

Figure 21. As it lies to the left of the left chain warp thread, it comes up between the crossed chain warp threads. By the movement of the tuft yarn just indicated, we complete the eye 14a and lay the foundation for the completion of the loop 14b.

Pile wire 85a and weft thread 75b are inserted in the position of the threads seen in Figure 21 and the loop 14b is completed by beating up 10 this pile wire and weft thread. The pile wire 85a and weft 75b are beaten up between the positions of Figures 21 and 22 and while the beat is up the needle drops, carrying the tuft yarn down and uncrossing the chain warp threads 10 and 11. This completes loop 14c and part of the eye 14d.

The needle in Figure 22 is now shown in its lowermost position to the left of the left-hand chain warp thread 11. When it dropped it 20 allowed the chain warp threads 10 and 11 to uncross, and also in dropping carried with it the stuffer warp thread 72.

After the return of the lay to the position of Figure 23, a weft thread 16b is inserted which, 25 as seen from Figure 23a, is the weft thread to be included along with chain warp thread 10 in the eye 14d. This weft thread is next beaten up.

While the weft thread 16b is being beaten up, the shed is changed from the position of Figure 30 23 to the position of Figure 24, with the chain warp 10 again above chain warp 11. As the warp threads are being shedded, the needle rises to its uppermost position, carrying the tuft yarn and stuffer warp thread to the position seen in Figure 25, in position laterally between the two uncrossed chain warp threads. In this position of the threads shown in Figure 25, the pile wire 85b and the weft thread 75c are inserted and are subsequently beaten up to the position of the 40 parts seen in Figure 18. This completes the eye 14d.

It will be noted during this operation—and will be much more clear from Figure 30—that in this operation the completion of the eye of one 45 knot is followed by the formation of the eye of the next knot and that the completion of the loop of the second knot is followed by the formation of the loop of the third knot, the knots alternating in their direction of facing in successive knots along the lengths of the warp threads 50 upon which the knots are formed.

From Figure 30, starting at the left hand side and moving toward the right, the eye 14a, which is the first part of the knot formed in the first 55 knot, terminates in the loop 14b. The tuft 88a before cutting was continuous with the adjoining tuft of the next knot to the right. The first knot was completed by the formation of the loop of the knot 14b and the first part of the middle knot to be formed is the loop. This middle knot is completed by the formation of its eye 14d, and the last knot at the right starts with the eye 14a and is completed by formation of the loop.

The tufts between the eyes of the middle and 65 third knots are uncut, the question of cutting or not cutting the tuft being determined by the fabric designer. The opposite facing of the knots is seen from the fact that the first and second of these knots are back to back, whereas the 70 second and third of these knots face front to front. The third and fourth knots again would be back to back, and so on.

The stuffer warp threads appear in Figure 30 but do not appear in Figure 33 and need not be 75 used in the form of Figure 30.

If the stuffer warp threads of Figure 30 be omitted, it will not change the structure of the knot in any way. The loom would operate the same. However our method of manufacture results in stuffer warp threads, when used, being 5 interwoven much more fully with the chain warp threads and weft threads than in other fabrics. There will be no difference, however, in the operation of the loom whether the stuffer warp threads be present or not; and these stuffer warp threads 10 have been omitted in the fabric of Figure 33.

The fabric of Figure 33 is woven by the operation shown in Figures 26-29 and differs from the fabric seen in Figure 30 in addition to the absence of stuffer warp threads, in that no weft threads 15 have been passed through the knots in Figure 33. The same number of weft threads are shown in Figure 33, but two shots of weft threads are passed together in Figure 33 in the positions of those 20 weft threads in Figure 30 which do not pass through the eyes of the knots.

It will be noted that the transition from Figure 31 to Figure 34 represents two changes in that Figure 30 shows the two weft shots inserted with 25 the same chain warp thread shedding as one over and one under the tuft yarn and as one over and one under the stuffer warp thread, whereas Figure 34 shows both weft shots for the same chain warp thread shedding under the tuft yarn and does not 30 show any stuffer warp thread. Figure 34a has been inserted for the purpose of showing the construction when the stuffer warp thread is used but when the two weft shots lie both under the tuft yarn, showing the fabric of Figures 33, 34, 35 and 35 thus in Figure 34a with, and in Figure 34 without, a stuffer warp thread. The reference characters shown in Figure 34a are intended to be 35 the same for the same parts as in Figure 34 and therefore will require no further description here. 40

In Figure 26, we have started with a knot already formed, as distinguished from starting from a plain weave in Figure 18, and have just beaten up weft thread 75b and pile wire 85a, shown by dotted position of the lay, the chain warp 45 threads—there are now no stuffer warp threads—and tuft yarn being in the same positions seen in Figure 18.

The lay then falls back to the position shown in full lines in Figure 26.

A weft thread 16b is inserted and is beaten up 50 and the needle is dropped. The needle is shifted to the right beneath right-hand chain warp thread 10, partially forming the eye 14g. The chain warp threads are resheded so that with the lifting of the needle the upper end of the 55 needle is high enough to laterally engage the chain warp thread 10 and to carry it under chain warp thread 11 and to the left to a position beyond the chain warp thread 11 at the left, where it is raised between crossed warp threads. This completes the eye 14g and partially forms the loop 14h. With the chain warp threads in the 60 position seen in Figure 28, pile wire 85b is inserted and weft thread 75c is placed. The weft thread 65 and pile wire are then beaten up to the position seen in Figure 29.

Dropping of the needle between the positions of Figures 28 and 29 allows the chain warp threads to uncross completing loop 14e and partially completing eye 14f.

The lay falls back to the dotted position of Figure 29 when another weft thread 16c is inserted and this weft thread is beaten up.

It will be noted from these figures, and from 75

Figures 33-35 as is true also of Figures 18-25 and 30-32, that in each case the pile wires are holding points at which the tuft yarn is held above the fabric, while the operations of tying knots upon the warp threads, or upon the warp threads and weft threads, are performed, and that each loop about a pile wire comprises parts, namely tufts, from adjoining knots.

It will also be understood that other modifications can be resorted to by proper changes in cams, to insert only one shot or a multiple number of shots of weft threads between each row of tufts or between each row of knotted tuft loops and eyes.

15 While the invention has been described in connection with a particular embodiment and in connection with a particular type of machine, it will be understood that it is capable of various further uses and modifications and that this application is intended to cover any variations, uses or adaptations of this invention, following, in general, the principles of the invention and including such departures from the present disclosure as come within the known or customary practice 20 in the art of weaving and as may be applied to the essential features herein set forth and as fall within the scope of the invention and of the appended claims.

30 In view of our invention and disclosure, variations and modifications to meet individual whim or particular need will doubtless become evident to others skilled in the art, to obtain all or part of the benefits of our invention without copying the structure shown, and we, therefore, claim all 35 such in so far as they fall within the reasonable spirit and scope of our invention.

Having thus described our invention what we claim as new and desire to secure by Letters Patent is:

40 1. A loom for weaving knotted pile fabrics having means for supporting and vertically manipulating chain threads, means for introducing weft threads within sheds formed by the chain threads, means for introducing and subsequently withdrawing pile wires, means for beating up the weft threads and pile wires, and support for a continuous tuft yarn supply, and means operated from beneath the chain threads and capable of extending above the chain thread shed having 45 eyes for the tuft yarn and adapted to engage the chain threads to shift them laterally and to control the lateral and up and down positions of the tuft yarn, whereby the chain threads are crossed, one of a pair with its mate and the tuft 50 yarn is looped from end to end of the crossings.

55 2. A loom for weaving knotted pile fabrics having means for supporting and vertically manipulating chain warp threads, means for introducing weft threads within sheds formed by the chain warp threads, means for introducing and subsequently withdrawing pile wires, means for beating up the weft threads and pile wires and support for a continuous tuft yarn supply, a plurality of needles having eyes through which the continuous tuft yarn passes, one tuft yarn through each eye, laterally reciprocating mechanism for the needles and up and down reciprocating mechanism for the needles, whereby the needles can be moved up and down with respect to the chain warp threads and laterally to different lateral positions with respect to the chain warp threads.

60 3. A loom for weaving knotted pile fabrics having means for supporting and vertically manipulating chain warp threads, means for introducing

weft threads within sheds formed by the chain warp threads, means for introducing and subsequently withdrawing pile wires, means for beating up the weft threads and pile wires and support for a continuous tuft yarn supply and tuft 5 yarn manipulating means for shifting one of the chain warp threads with respect to the other and thus crossing the chain warp threads.

4. A loom for weaving knotted pile fabrics having means for supporting and vertically manipulating chain warp threads, means for introducing weft threads within sheds formed by the chain warp threads, means for introducing and subsequently withdrawing pile wires, means for beating up the weft threads and pile wires and support for a continuous tuft yarn supply and tuft 10 yarn needle manipulating means movable laterally and up and down for shifting one chain warp thread with respect to the other and passing the tuft yarn through between both the crossed and 15 uncrossed chain warp threads.

5. A loom for weaving knotted pile fabrics having means for supporting and vertically manipulating chain warp threads, means for introducing weft threads within sheds formed by the 20 chain warp threads, means for introducing and subsequently withdrawing pile wires, means for beating up the weft threads and pile wires and support for a continuous tuft yarn supply, and needles introduced from below the chain warp 25 threads having eyes for the tuft yarn threads and movable laterally and up and down for crossing the chain warp threads and for shifting the tuft yarn up and down and laterally outside of the chain warp threads of the pair or between 30 the crossed or uncrossed chain warp threads.

6. In a loom for weaving knotted pile fabrics, a loom frame, means for supporting and upwardly and downwardly manipulating the warp threads for the production of the fabric, means 40 for introducing weft threads to sheds formed by the chain warp threads for the production of the fabric body or backing, a lay, actuating mechanism therefor, a tuft yarn source supplying tuft yarn parallel with the chain warp threads, means 45 for introducing pile wires to the pile forming sheds of the tuft yarn, means for withdrawing the pile wires from the fabric, separate means for lifting and lowering and for laterally shifting the individual tuft yarns and means for laterally 50 shifting one warp thread of each pair with respect to the other warp thread, whereby the chain warp threads are crossed and the tuft yarn may be manipulated with respect to the crossed and uncrossed chain warp threads.

7. In a loom for weaving knotted pile fabrics, mechanism for holding and shedding warp threads, means for inserting weft thread within the sheds of the warp threads, a lay, a pile yarn source, laterally and vertically movable pile yarn 60 control mechanism laterally engaging the warp threads and means for lifting and lowering and laterally moving the control mechanism to engage and shift the warp threads, whereby warp threads are crossed one under another in the 65 warp thread pairs and the pile yarn is shifted with respect to the crossed and uncrossed warp threads forming knots and pile wire mechanism adapted to insert a pile wire under the pile yarn and hold it in position.

8. A loom for weaving knotted pile fabrics comprising mechanism for holding and weaving chain warp threads and weft threads and tuft 70 yarn and pile wire inserting mechanisms in combination with a plurality of upwardly directed 75

needles apertured to pass a tuft yarn through each needle, reciprocating means for laterally shifting the needles and reciprocating means for lifting and lowering the needles whereby the 5 needles carrying the tuft yarn are shifted to engage one chain warp thread each of each chain warp thread pair to cross the chain warp threads and pass the tuft yarn around the crossing point.

9. A loom for weaving knotted pile fabrics having means for supporting and vertically manipulating chain warp threads, means for introducing weft threads within sheds formed by the warp threads, means for introducing and subsequently withdrawing pile wires, means for beating up the weft threads and pile wires and support for a continuous tuft yarn supply, means for supporting stuffer warp threads, a plurality of needles and shifting means for raising and lowering the needles, the needles having eyes for the 10 tuft yarns and slots giving up and down lost motion for the stuffer warp threads and, beyond the lost motion, carrying the stuffer warp threads with the needles in an upward and downward movement.

10. A loom for weaving knotted pile fabrics having means for supporting and vertically manipulating chain warp threads, means for introducing weft threads within sheds formed by the warp threads, means for introducing and subsequently withdrawing pile wires, means for beating up the weft threads and pile wires and support for a continuous tuft yarn supply, means for supporting stuffer warp threads, a plurality of needles, shifting means for moving the needles laterally 15 and shifting means for raising and lowering the needles, the needles having eyes for the tuft yarns and slots giving up and down lost motion for the stuffer warp threads and, beyond the lost motion, carrying the stuffer warp threads with the 20 needles in an upward and downward movement.

11. A loom for weaving knotted pile fabrics having means for supporting and vertically manipulating chain warp threads, means introducing weft threads within sheds formed by the warp threads, means for introducing and subsequently withdrawing pile wires, means for beating up the weft threads and pile wires and support for a continuous tuft yarn supply, means for supporting stuffer warp threads, a plurality of needles 25 and reciprocatory means for moving the needles up and down, the needles having eyes for the tuft yarns and slots tapered from a narrower upper part to a wider lower part for stuffer warp threads, giving up and down lost motion for the stuffer warp threads and, beyond the lost motion, carrying the stuffer warp threads with the 30 needles in upward and downward movement.

12. A loom for weaving knotted pile fabrics having means for supporting and vertically manipulating chain warp threads, means for introducing weft threads within sheds formed by the warp threads, means for introducing and subsequently withdrawing pile wires, means for beating up the weft threads and pile wires and support for a continuous tuft yarn supply, means for supporting stuffer warp threads, a plurality of needles, reciprocating means for moving the needles laterally and reciprocatory means for moving the needles up and down, the needles having eyes for the tuft yarns and slots tapered from a narrower upper part to a wider lower part for stuffer warp threads, giving up and down lost motion for the stuffer warp threads, 35 and beyond the lost motion, carrying the stuffer 40

warp threads with the needles in upward and downward movement.

13. A loom for weaving knotted pile fabrics having means for supporting and vertically manipulating chain warp threads, means for introducing weft threads within sheds formed by the warp threads, means for introducing and subsequently withdrawing pile wires, means for beating up the weft threads and pile wires, and support for a continuous tuft yarn supply, supports for stuffer warp threads, a fixed reed for guiding the warp threads, needles having eyes through which the tuft yarns pass and having lost motion control for upward and downward movement of the stuffer warp threads with upward and downward movement of the needles and shifting means for manipulating the needles upwardly and downwardly and laterally. 15

14. A loom for weaving knotted pile fabrics having means for supporting and vertically manipulating chain warp threads, means for introducing weft threads within sheds formed by the warp threads, means for introducing and subsequently withdrawing pile wires, means for beating up the weft threads and pile wires and support for a continuous tuft yarn supply, means for supporting stuffer warp threads and needle means for shifting the tuft yarns and stuffer warp threads up and down and laterally, having lost motion connection with the stuffer warp 20 threads to reduce their up and down movement. 25

15. A loom for weaving knotted pile fabrics having means for supporting and vertically manipulating chain warp threads, means for introducing weft threads within sheds formed by the warp threads, means for introducing and subsequently withdrawing pile wires, means for beating up the weft threads and pile wires and support for a continuous tuft yarn supply, means for supporting stuffer warp threads, means for laterally fixing positions of the eyes of the heddles at uniform spacing to guide the warp threads and needle means for shifting the tuft yarns and stuffer warp threads up and down with lost motion to reduce the up and down movement of the stuffer warp threads, and means for shifting the tuft yarns and stuffer warp threads laterally with respect to the chain warp threads. 35 40 45

16. A loom for weaving knotted pile fabrics having means for supporting and vertically manipulating chain warp threads, means for introducing weft threads within sheds formed by the warp threads, means for introducing and subsequently withdrawing pile wires, means for beating up the weft threads and pile wires, and support for a continuous tuft yarn supply, means for supporting warp threads, fixed reeds for guiding the warp threads against lateral displacement, the heddle eyes being uniformly spaced, fixedly spaced needles for shifting the positions of the tuft yarns and stuffer warp threads and providing vertical lost motion to reduce the movement of the stuffer warp threads and means for shifting the needles laterally. 50 55

17. A loom for weaving knotted pile fabrics having warp thread supporting and shedding means, weft thread supporting and inserting means and tuft yarn supporting means, and needle means for laterally and vertically manipulating the tuft yarn and for shifting the warp threads by lateral engagement with them, the operation of the needle and the operation of weft insertion being so timed that the needle means crosses the warp threads and passes tuft 60 65 70 75 80 85 90 95 100 105 110 115 120 125 130 135 140 145 150 155 160 165 170 175 180 185 190 195 200 205 210 215 220 225 230 235 240 245 250 255 - inserted sometimes within and sometimes without the knot formed.
18. A loom for weaving knotted pile fabrics having warp thread supporting and shedding means, weft thread supporting and inserting means and tuft yarn supporting means, and needle means for laterally and vertically manipulating the tuft yarns up and down and laterally, and laterally engaging the warp threads to shift them whereby the needles are used to cross the warp threads and to pass tuft yarn around the crossing points, the needle operation and the weft insertion being so timed as to pass weft thread wholly between the knots formed.
19. A needle frame for use in a knotted fabric loom having a guideway in the bottom of the frame, a needle bar adapted for movement in the guideway, a plurality of uniformly spaced needles carried by the bar each having an eye for tuft yarn manipulation and a slot below the eye and shifting means for the needle bar adapted to move it in the guideway in a direction across the loom and back again.
20. A needle bar frame for use in a knotted fabric loom, means for lifting and lowering the frame, a bar movable in the frame in a direction across the loom and back again, a plurality of uniformly spaced needles carried by the bar each having an eye for tuft yarn manipulation and a slot below the eye and shifting means for the needles of the bar fixed in vertical position and having guideways for the needles permitting their movement up and down in the guideways, and controlling the lateral movement of the needles by the shifting means.
21. In a loom for weaving knotted pile fabrics, a plurality of needles having eyes for pile yarn manipulation and a slot below the eye, a holder for the needles spacing them uniformly, reciprocating means for raising and lowering the needles, guides for the needles supporting them against lateral movement with respect to the guides and reciprocating means for shifting the guides to control lateral movement.
22. In a loom for weaving knotted pile fabrics, a plurality of needles having eyes and adapted to manipulate the tuft yarns up and down and having slots in them below the eyes for stuffer warp thread passage, the slots being tapered to widen downwardly, connection between the needles spacing them uniformly, guides for the needles supporting them against lateral movement with respect to the guides and reciprocating means for lifting and lowering the needles and reciprocating means for laterally shifting the needles in a direction across the loom and back while permitting up and down movement of the needles within the guides.
23. A loom for weaving knotted pile fabrics having means for supporting and vertically manipulating chain warp threads, means for introducing weft threads within sheds formed by the chain warp threads, means for introducing and subsequently withdrawing pile wires, means for beating up the weft threads and pile wires and support for a continuous pile yarn supply, a plurality of needles adapted to guide the pile yarn, means for lifting and lowering the needles and means for laterally shifting the needles, whereby the needles can be lifted to shed pile yarn for passage of the pile wires and can be lowered, with or without crossing of the chain warp threads by the needles.
24. The method of weaving knotted pile fabric in a loom having needles by which tuft yarn is guided and manipulated which consists in passing a continuous tuft yarn down between the threads of a pair of warp threads, subsequently crossing the threads by the needle and passing the tuft yarn up between the pair of threads on the opposite side of the crossing, inserting a pile wire in the shed formed above the warp shed and between the warp threads and the tuft yarn and beating up the pile wire to the fell, in passing the tuft yarn over the rear surface of the pile wire and in repeating the operation.
25. The steps in the method of weaving a knotted pile fabric, which include passing a continuous tuft yarn between the threads of a pair of warp threads, subsequently crossing the warp threads and passing the tuft yarn back between the threads of the pair on the opposite side of the crossing, inserting a pile wire in the shed formed above the warp shed and between the warp threads and the tuft yarn and beating up the pile wire to the fell and passing the tuft yarn over the rear surface of the pile wire into position to repeat the operation, weft being inserted over the tuft yarn during the operation.
26. The steps in the method of weaving a knotted pile fabric from continuous tuft yarns guided and manipulated by needles and pairs of warp threads, using weft threads and pile wires, which include starting with the tuft yarn above the warp threads, passing it downwardly between the warp threads while in their uncrossed position, crossing the warp threads by a needle, bringing the tuft yarn upwardly between the crossed warp threads, releasing the crossed warp threads and beating up the pile wire and knot formed.
27. The method of forming Sehna type knots in a loom for weaving knotted pile fabrics, which includes crossing the warp threads for each knot to be formed, in manipulating the tuft yarn about the warp threads to pass it between the crossed warp threads back of the crossing, in passing weft over the tuft yarn while it is lowered to pass the tuft yarn through the crossed warp threads, in lifting the tuft yarn and passing it about a pile wire and in releasing the crossing to form the knot, whereby both warp threads and the weft thread are included within the knot.
28. The method of forming a Sehna type knot in a loom for weaving knotted pile fabrics, from continuous tuft yarn, which consists in supporting the tuft yarn at both ends of the knot from pile wires, in intermediately crossing the warp threads, lowering the tuft yarn and passing it as a loop from end to end of the crossing of the crossed warp threads and subsequently raising it, in passing weft thread above the tuft yarn while the tuft yarn is lowered, in passing weft thread also below the tuft yarn to be bound into the fabric and in releasing the crossing.
29. In the weaving of knotted pile fabric from chain warp threads, stuffer warp threads, weft threads and continuous tuft yarn, the method which consists in forming a crossing in the chain warp threads in front of the lay by physical crossing of the warp threads back of the lay, in manipulating the tuft yarn from a point back of the lay to loop it about the crossed warp threads from end to end of the crossing, in inserting pile wire to hold the tuft yarn, in releasing the crossing of the warp threads to change the loop about the crossing to a knot, in inserting weft both over and under the stuffer warp threads, two weft insertions for each knot and in repeating the operation.

30. In the weaving of knotted pile fabric from chain warp threads, weft threads, stuffer warp threads, weft and continuous tuft yarn, the method which consists in forming a crossing in the warp threads in front of the lay by physical crossing of the warp threads back of the lay, in manipulating the tuft yarn from a point back of the lay to loop it about the crossed warp threads from end to end of the crossing, in inserting pile wire to hold the tuft yarn, in releasing the crossing of the warp threads to change the loop about the crossing to a knot, in inserting weft both over and under the stuffer warp threads, two weft insertions for each knot and 10 in repeating the operation, the loop of one knot being constructed before its eye and the eye of the next knot of the next row being constructed before its loop, and so on.

31. In the weaving of knotted pile fabric from warp threads, weft threads and continuous tuft yarn, the method which consists in forming a crossing in the warp threads in front of the lay by physical crossing of the warp threads back of the lay, in manipulating the tuft yarn from a point back of the lay to loop it about the crossed warp threads past the crossing, in inserting pile wire to hold the tuft yarn, in releasing the crossing of the warp threads to change the loop about the crossing to a knot and in repeating the operation, weft being inserted over the tuft yarn to pass it through the knot.

32. The method of forming knotted tufts about warp threads in a loom for weaving knotted pile fabrics having means for supporting and vertically manipulating warp threads, means for introducing weft threads within sheds formed by the warp threads, means for introducing pile wires and subsequently withdrawing the pile wires and supporting means for tuft yarn source of supply and for the tuft yarn carried thereby, which consists in crossing the warp threads and uncrossing them for each cycle of knots formed, manipulating the continuous tuft yarn laterally across a warp thread in one direction and then laterally back and vertically as distinguished from longitudinally, to pass the tuft yarn as a loop from one end of the warp thread crossing nearer to the fell to the other end, forming a loop during the time the warp threads are crossed which forms a Sehna knot when the warp threads are uncrossed.

33. The method of forming knotted tufts about warp threads in a loom for weaving knotted pile fabrics having means for supporting and vertically manipulating warp threads, means for introducing weft threads within sheds formed by the warp threads, means for introducing pile wires and subsequently withdrawing the pile wires and supporting means for tuft yarn source of supply and for the tuft yarn carried thereby, which consists in crossing the tuft yarn with a warp thread and crossing the warp threads, in passing the tuft yarn about the crossing end for end and later uncrossing the warp threads, manipulating the continuous tuft yarn laterally and vertically by needles as distinguished from manipulating the yarn longitudinally to pass the tuft yarn around from one end of the warp thread crossing to the other, thus forming a loop during the time the warp threads are crossed which forms a Sehna knot when the warp threads are uncrossed, the warp threads being shedded, weft thread being inserted with every insertion of pile wire and between each two insertions of pile wire before the warp threads are reshaded.

34. The method of forming knotted tufts about warp threads in a loom for weaving knotted pile fabrics having means for supporting and vertically manipulating warp threads, means for introducing weft threads within sheds formed by the warp threads, means for introducing pile wires and subsequently withdrawing the pile wires and supporting means for a tuft yarn source of supply and for the tuft yarn carried thereby, which consists in crossing the tuft yarn with respect to a warp thread, then crossing the warp threads, passing the tuft yarn about the crossing from end to end and later uncrossing the warp threads, manipulating the continuous tuft yarn laterally and vertically by needles as distinguished from manipulating the yarn longitudinally to pass the tuft yarn across from one end of the warp thread crossing to the other, thus forming a loop during the time the warp threads are crossed which forms a Sehna knot when the warp threads are uncrossed, the warp threads being shedded and weft thread being inserted with every insertion of pile wire and between each two insertions of pile wire before the warp threads are reshaded, and the crossing of the warp threads being effected by manipulation back of the lay.

35. Steps in the method of forming knotted tufts about warp threads in a loom for weaving knotted pile fabrics which consist in crossing the warp threads by lateral warp thread movement back of the lay and uncrossing them for each pair of knots formed, in manipulating the continuous tuft yarn back of the lay laterally and vertically by needles as distinguished from manipulating the yarn longitudinally to pass the tuft yarn across from one end of the warp thread crossing to the other, forming a loop during the time the warp threads are crossed, which forms a knot when the warp threads are uncrossed, the warp threads being shedded and weft thread being inserted under the tuft yarn with every insertion of pile wire and, also under the tuft yarn, between each two insertions of pile wire.

36. The method of forming knotted tufts about warp threads in a loom for weaving knotted pile fabrics, which consists in crossing the warp threads by lateral warp thread movement back of the lay and uncrossing them for each cycle, in manipulating the continuous tuft yarn back of the lay laterally and vertically as distinguished from longitudinally to pass the tuft yarn beneath the crossing from one end of the warp thread crossing to the other, forming a loop during the time the warp threads are crossed, which forms a knot when the warp threads are uncrossed, the warp threads being shedded and weft thread being inserted under the tuft yarn with every insertion of pile wire and over the tuft yarn between each two insertions of pile wire.

37. The method of forming knotted tufts about warp threads in a loom for weaving knotted pile fabrics, which consists in shedding the warp threads and the tuft yarn above the warp threads, in passing weft between the warp threads, in inserting a pile wire between the warp threads and the tuft yarn, in beating up the weft thread and pile wire, in passing the tuft yarn down between the parallel warp threads of the upper and lower shed, in inserting a weft thread over the tuft yarn and in beating up the weft thread and holding it in the beaten up position, in crossing the tuft yarn and one warp thread under the other warp thread by engagement of the tuft yarn carrier with the warp thread which is moved

to effect the crossing, in reshedding the warp threads during the crossing, in forming a shed of the tuft yarn above the warp threads, in passing weft thread between the shedded warp threads and inserting a second pile wire within the shed of the tuft yarn above the warp threads in inserting weft under the yarn, in beating up the weft thread and pile wire, holding the weft in place by the beat of the lay, in dropping the tuft yarn between the warp threads and permit-

ting the crossed warp threads to uncross, in inserting weft within the shedded warp threads over the yarn, in beating up the weft thread and holding it in beaten up position, in reshedding the warp threads and in passing the tuft yarn up 5 between the uncrossed warp threads of a pair to form a shed above the warp thread sheds and in continuing the operation.

WALTER A. RICE.
